UNITED STATES PATENT OFFICE.

WILLIAM CHESTER WOOD, OF BALTIMORE, MARYLAND, ASSIGNOR TO THE CROWN CORK AND SEAL COMPANY, OF BALTIMORE, MARYLAND, A CORPORATION OF MARYLAND.

SODA-WATER-BOTTLING MACHINE.

No. 863,127.

Specification of Letters Patent.

Patented Aug. 13, 1907.

Application filed November 5, 1904. Serial No. 231,572.

To all whom it may concern:

Be it known that I, WILLIAM CHESTER WOOD, a citizen of the United States, residing at Baltimore, in the State of Maryland, have invented new and useful Improvements in Soda-Water-Bottling Machines, of which the following is a specification.

In soda-water bottling machines of a well known type, the filling head carries a pendent pointed syrup-tube in communication with a suitable source of supply controlled by a suitable valve and hand lever. These machines are so organized that either the filling head, or a bottle supporting table is so movable that while one bottle having already received its syrup may be receiving water and gas and be in position to be capped, a second bottle in proper relation to the syrup-tube may at the same time be charged with syrup in proper quantity. Machines of the character indicated were disclosed in U. S. Letters Patent No. 608,158; issued to William Painter, July 26th, 1898, to which reference may be had if need be for further knowledge of such machines.

In an application for patent filed by me October 21, 1904, Serial No. 229,414, I disclosed certain improvements in machines of the kind referred to, having in view simplicity and economy in the construction of syrup tubes, an increased measure of safety both to the tubes and bottles, and greater facility in operating the machines. My said prior improvements involved the use of a novel guide carried on the head of the machine and so constructed and arranged with relation to the syrup-tube as to cause a safe and reliable registration of the tube with bottles and afford a free and unobstructed annular passage for a bottle head between the guide and the tube, the latter being well within the bottle.

In accordance with my present invention, a guide, which may be termed "bell-shaped", is slidably mounted on the pendent syrup-tube, and after doing its duty in guiding a bottle head so as to accurately receive and encircle the tube, it is supported upon and carried by the bottle head during the continued movement of the head or the table as the case may be, and until the bottle has received its syrup. This guide is so mounted on the tube as to admit of a slight rocking or vibratory movement for avoiding an adhesive tendency should the exterior surface of the tube get smeared with syrup. For removing undue sugary accretions from the outside of the tube, the guide is provided with an interior annular scraper which during each downward movement of the guide on the tube, removes therefrom more or less of the semi-solid adhering matter, which will be free to drop within a bottle occupying the guide.

To more particularly describe my invention, I will

refer to the accompanying drawings, and after a detailed description, the features deemed novel will be duly specified in clauses of claim hereunto annexed.

Referring to the drawings, Figure 1 illustrates partly in front elevation and partly in section, so much of the filling head and table of a soda-water bottling machine as is deemed necessary for the purposes of this specification, the syrup-tube and the guide thereon being shown in section, and the table having two bottles thereon standing in the usual two contact bottle gage; it being understood that the machine contains operative mechanism for causing the head and table to assume co-operative positions, with one bottle encircling the tube for receiving syrup, and a second bottle (already syruped) with its head within the filling chamber to receive water and gas, and while still tightly inclosed in said chamber, to receive its closure or sealing device. Fig. 2 illustrates the guide on an enlarged scale, partly in side elevation and partly in section, and Fig. 3 is a top view thereof.

The filling head A is provided with the usual ducts or passages for the soda-water, and a filling chamber a and also a hand lever b which enables the syrup, gas and water to be appropriately controlled. The table B with its bottle gage C having its two gaging contacts c and c' at its opposite ends, are as described in said hereinbefore mentioned patent. The syrup tube D, pendent from the head of the machine, differs from the tube of said patent in having an open mouth and no pointed tip, and from the tube of my said pending application in having a strong fixedly mounted collar d at its lower end, affording a shoulder (at its upper edge) for supporting and retaining the bell-shaped guide E on the tube. This guide E has a thick and quite heavy mass of metal at its top for enabling it to resist adhesive tendencies and to slide to its supporting collar d on being released by a bottle which has previously been guided into line with the tube by the interior flared annular surface of the guide. The interior diameter of the guide at a point slightly below the top wall of the cavity is such that the periphery of a bottle lip will engage with the guide and lift it from the collar on which it is normally supported. The flare of the guide, if substantially as indicated, will assure proper guidance for such bottles as are capable of use although so far untrue as to form that they cannot stand upright in the gage C, and enable their heads, as well as the heads of perfect bottles, to take proper bearing near the top of the cavity without possibility of injurious contact with the end of the syrup tube.

The central hole e in the guide, is slightly flared for nearly its whole length from the top downwardly to near its bottom, where it is straight and sufficiently larger than the tube to admit of a free slidable move-

ment thereon, and at the same time permit the guide to rock or vibrate slightly on the tube to the extent afforded by the flare or taper of the hole. Surrounding the hole within the guide is an annular scraper *f*, having its short edge closely adjacent to the outside of the tube. This scraper or clearer may be separately constructed and fixedly inserted in the guide, but with a view to simplicity and economy it may be integral with the guide which is composed of brass or any suitable material which is heavy and hard enough to serve its purpose.

The outer annular surface of the scraper is beveled as indicated for inducing a chiseling clearance from the edge of such sugary matter as it may remove from the surface of the tube. If after use, the tube and guide may not have been properly cleansed, the guide should be reciprocated by hand a few times, to assure its free downward movement. It sometimes occurs that an extra long bottle will be placed at the tube when an extra short bottle occupies the filling chamber, and

in such contingency, the vertical dimensions of the metal necessary for affording a hole long enough to secure a proper slide bearing between the guide and tube, may cause a stopping abutment of the long bottle, and prevent the lip of the short bottle from occupying its proper position for receiving its closure, in which case the long bottle must be removed for enabling the other bottle to be capped or otherwise sealed.

Having thus described my invention, I claim:

In a soda-water bottling machine, the combination with 30 a syrup-tube, of a bell-shaped guide slidably mounted on said tube, capable of rocking or vibrating thereon, and provided with an interior annular scraper for clearing sugary matter from the exterior surface of the tube during the downward movement of the guide, substantially as described.

In testimony whereof I have hereunto set my hand in presence of two subscribing witnesses.

WILLIAM CHESTER WOOD.
